(57) **CLAIM**

The ornamental design for a display screen or portion thereof with a graphical user interface, as shown and described.

DESCRIPTION

The FIGURE is a front view of a display screen or portion thereof with a graphical user interface showing the new design.

The broken lines at the peripheries of the FIGURE illustrate a display, and the remainder of the broken lines in the FIGURE illustrate portions of the graphical user interface. None of the broken lines form part of the claimed design.
